17 Claims. (Cl. 209—423)

1

This invention relates to apparatus for separating materials composed of constituents of different specific gravities, and more particularly to jigs for effecting the wet separation of minerals to be recovered from other constituents of ores.

In separating minerals from ores by the wet method termed jiggling, the ore is usually crushed and sized to obtain free particles of its constituents in a mechanical mixture. After proper preparation, the mixture is deposited in a tray having a foraminous support such as a screen or grid therein whereon the mixture is stratified under water by employing alternate periods of agitation and settling. The ideal agitating phase is of a type which will leave the entire mixture suspended in the liquid in a loose, undisturbed body. The settling phase, following the phase of agitation, allows the separate particles to descend at a rate approximately agreeing with an empirical physical formula known as Stoke's Law, which defines the relationship between particle density, liquid density and ultimate velocity of descent when dealing with small spheres of one size. In actual jiggling practice the settling rate of each particle is affected not only by its density and the density of the suspending medium, but also by its size and shape. Thus, the end result is that strata of particles tend to arrange themselves upon the support in direct relationship to their settling rates.

Heretofore, separation of materials by jiggling has generally been accomplished by imparting simple harmonic motion vertically to the tray and the screen or grid upon which the ore or other material is deposited. Separation of the constituents of the mixture has not been difficult if there has been a considerable uniform difference in settling rates of the different materials being acted upon. Furthermore, should a wide difference exist between the specific gravities of the constituents, a considerable range of particle sizes can be separated at one and the same time. When the settling rates of the several materials differ uniformly but only to a slight degree, separation by jiggling, as heretofore practiced, becomes difficult. Close sizing of particles and smaller vibration amplitude become increasingly necessary in an effort to induce stratification and subsequent separation, this being especially true when treating finer sizes.

As particle size decreases, so must the openings in the foraminous support. This usually means a decrease in the percentage of effective open area of the support. The result is greater resistance to the passage of water or other liquid through

2

the support. Mechanical drag is the consequence of this condition, causing particles to follow the support as it descends, and stratification with relation to free falling descent is impossible.

To counteract this drag the operator is compelled to speed up the rate of vibration to force the liquid through the foramina at a higher velocity. This procedure also deters stratification, since if the downward phase of a simple harmonic vibration is increased, so is the upward phase; thus the amount of time allowed for the particle to fall freely and stratify is shortened.

The present invention provides a novel and improved separator of the jig type which enables the separating action to be accomplished more effectively and efficiently, especially in separating materials in which the specific gravity differential of the intermixed constituents is relatively small, by imparting to the foraminous support a novel differential motion the characteristics of which may be varied to suit the nature of the ore to be treated.

A primary object of the present invention is to provide, in a separator of the jig type, means for imparting a suitable differential motion to the foraminous support whereby particles of a mixture of ore or similar material having but a small gravity differential may be readily and efficiently separated.

30 A more particular object of the invention is to provide, in a jig equipped with means for imparting a differential motion thereto, means for changing the characteristics of the motion to that most effective for separation of the ore or other material to be treated.

35 Another object is to provide, in a separator of the type described, means whereby the length of the vibratory strokes imparted to the foraminous support may be readily adjusted, after the characteristics of the stroke have been determined and fixed, without changing the characteristics of the strokes.

40 A further object is to provide novel means for changing the length of the strokes which means may be readily operated while the separator is in operation.

45 A further object is to provide novel means for supporting the foraminous support and associated parts in order to render said support responsive to the minutest variations in the characteristics of the movements imparted thereto.

With these objects in view the invention comprises generally a separator of the jig type having a tray provided with a screen, grid or other

50 suitable foraminous support for the material de-

posited therein, resilient means supporting the tray in a water bath and constantly tending to move the tray upwardly, in combination with novel means for effecting the desired variable detruson of the tray and for controlling the return upward movement thereof under the influence of the resilient tray supporting means.

The invention further comprises a separator of the above described type in which the characteristics of the motions may be varied to suit 10 the character of the ore or other material to be treated.

More specifically, the invention comprises a separator of the jig type having a foraminous ore or material supporting tray arranged in a water 15 bath, supporting means for the tray constantly tending to move the same upwardly, means for imparting novel differential strokes to the tray, and means for varying the characteristics of the strokes.

The invention further provides improvements in the structure of separators of the jig type whereby the stability of the vibratory tray and screen is enhanced, and the operation thereof improved generally.

To these and other ends, the invention consists in certain improvements and combinations and arrangements of parts, all as will herein-after appear, the features of novelty being pointed out more particularly in the claims at the end of this specification.

In the accompanying drawings which show the preferred embodiment of the invention:

Fig. 1 is a side elevation of a separator of the jig type constructed in accordance with the present invention.

Fig. 2 is an elevation of the front or discharge end of the separator.

Fig. 3 is a partial plan view of the separator shown in Figs. 1 and 2.

Fig. 4 is a vertical longitudinal section taken on the line 4—4 of Fig. 2.

Fig. 8 is a section on the line 8—8 in Fig. 7.

Fig. 9 is a vertical longitudinal section of the vibration generating mechanism taken on substantially the line 9—9 of Fig. 10.

Fig. 10 is a horizontal section of the same mechanism taken on the line 10—10 of Fig. 9.

Fig. 11 is a vertical transverse section taken on the line 11—11 of Fig. 9.

Fig. 12 is a detail section on the line 12—12 of Fig. 10, illustrating the cam shaft torsion spring and means for adjusting the power thereof.

Figs. 13 and 14 are details of the lower end of one of the stirrups which are fixed to the tray.

Fig. 15 is a plan view of the torque lever, a portion thereof being shown in section on the line 15—15 of Fig. 16.

Fig. 16 is a side elevation of the torque lever.

Fig. 17 is a transverse section of the torque lever taken on the line 17—17 of Fig. 16.

Figs. 18 to 22 inclusive are diagrams illustrating the development of the stroke characteristics.

Fig. 23 is a diagrammatic view illustrating generally the means for transmitting the strokes or vibrations from the power crank shaft to the tray screen support.

Similar parts are designated by the same reference characters in the several figures.

In the accompanying drawings, 15 indicates the main stationary supporting structure of the separator which is preferably constructed of two strips of plate steel which are bent to form halves of a rectangle, the meeting ends of the strips being welded together as at 20 to form a rigid casing having four walls 16, 17, 18 and 19. Each of these walls is provided with openings 21, 21a and 22, 22a, to provide access to the mechanism enclosed within the enclosing casing. The lower edge of the casing structure thus formed is preferably turned outwardly to form a base flange 23.

A hutch 24 of generally inverted pyramidal shape, and having discharge means is mounted in fixed position in the main stationary frame and is provided with water supply means, all as will be hereinafter described, the periphery of the hutch overhanging the upper edge of the supporting structure 20 and forming a flange 25, which is welded thereto.

Above the casing 15 and supported in a manner hereinafter described is a tray 26 into which the pulverized ore or other material to be treated is fed from a chute 27. The tray comprises a body portion 28 preferably of elongated rectangular form extending longitudinally of the separator and provided at its forward end with a downwardly inclined spout 29.

Arranged transversely of the body portion 28 at the junction thereof with said spout, is a gate frame 30 having a central discharge opening 31 for the concentrates or quickest settling constituents, and a pair of laterally disposed discharge openings 32 for the tailings or gangue. The discharges through said openings are controlled by adjustable gates or weirs 33 and 34 respectively, each having a suitable discharge aperture 35. Each gate or weir is independently adjustable by an adjusting screw 36 rotatable and threaded in a nut secured to a bracket plate 37 attached to the upper portion of the gate frame 30, the lower end of each screw being reduced in diameter to extend through a hole in the horizontal leg of an angle iron 36a welded to the upper part of the respective gate, the end of the screw below said leg being formed with a circumferential groove 36b in which a spring thrust washer 36c is pressed and which abuts against the underside of said leg of the angle iron.

A concentrate cup 40 is positioned behind the central or concentrate discharge weir, this cup being adjustable vertically by a screw 41 mounted in the bracket plate 37.

Communicating with and extending forwardly from the concentrate gate opening 31 is a discharge spout 42. This spout is arranged centrally within the spout 29, as shown in Figs. 2 and 3, and carries off the concentrate, discharging the same through an outlet 43 which extends through the bottom 44 of the chute 29.

A rectangular flange 47 extends from the level of the bottom 46 of the tray 26, this flange being coextensive in width with that of the body of the tray, and this flange extends longitudinally rearwardly from the gate end, as shown in Fig. 4. A foraminous support, such as a perforated screen plate or grid 48, fits within the upper portion of the flange 47 of the tray and is provided with a depending peripheral flange 49 which is secured to the walls of the flange 47, supporting the screen or grid on a level with, and forming a portion of the tray bottom 46. The forward end of the screen is spaced from the tray flange 47 a sufficient distance to permit the gates to extend down between this flange and the screen flange

49, thus providing for maximum range in adjustment of the gates although the lower ends of the gates will not be withdrawn from between these flanges when the gates are raised to their maximum height.

The perforations of the screen plate or grid may vary as to size and spacing according to the degree to which the ore or other material has been pulverized or the character thereof, and to this end the tray may be provided with a plurality of interchangeable screens or grids of different meshes and patterns.

The tray rests upon a support which comprises a rectangular frame 51 having lateral arms 52 which extend outwardly over and beyond the side elements of the supporting casing. (See Figs. 2 and 3.) The upper face of the frame 51 is formed with a continuous groove 53 having a gasket therein in which rest the lower edges of the flange 47. Eye bolts 54 pivotally connected to the frame 51 and engaging notched flanges 55 on the tray 26, hold the tray securely and rigidly in position on the supporting frame.

The supporting frame 51 is arranged substantially centrally within the upper end of the hutch 24, and a flexible diaphragm 57 of rubber or other flexible waterproof material closes the space between said frame and the top of the hutch. Holding strips 58, secured in place by bolts 59 fasten the outer edges of the diaphragm above the flange 25 of the supporting structure 15, and similar holding strips 60 and screws 61 secure the inner edges of the diaphragm to the under face of the frame 51.

According to the construction thus far described, it will be understood that water may be retained within the hutch 24 and extend upwardly through the tray frame 51 and screen 48 into the tray 26 where it may be maintained at the desired level by means of the adjustable weirs, so that stratification of the ore or material in the tray above the perforated screen plate or grid will take place under water.

The arms 52 of the tray supporting frame extend therefrom outwardly and are preferably inclined upwardly, and they terminate in horizontal flanges 63 to which pairs of spaced vertically disposed carrier rods 65 are secured adjustably. Preferably, the outer edges of the flanges are provided with notches 66 to receive threaded upper ends of the rods to facilitate assembly, and nuts 67 threaded on said ends securely clamp the flanges 63 adjustably to said rods.

The rods 65 extend downwardly through housings 70 secured to the outer sides of the supporting structure 15 for engagement with the actuating mechanism, as will be hereinafter described.

A spring-compression yoke 71 is mounted loosely upon each pair of rods 65 beneath the respective flanges 63, and between the ends of the yoke and the bottoms 72 of the housings 70 are compression springs 73 which constitute the resilient supporting means for the tray. The pairs of supporting springs 73 are spaced widely apart laterally of the separator, as shown in Figs. 2 and 3, and the rods of each pair are spaced apart a considerable distance longitudinally of the separator, as shown in Figs. 1 and 3, to give stability of support for the tray 26 and minimize tendency thereof to rock. An adjusting screw 74 is threaded centrally through each of the flanges 63 and bears upon the respective spring compression yoke 71, these screws providing means for loading or adjusting the power of the supporting springs 73. Adjustment of

5 the screw 74 will raise or lower the yoke 71 relatively to the flange 63 on the tray and thereby adjust the power of the springs 73 without disturbing the adjustment of the height of the tray by the nuts 67 and the level condition of the diaphragm 57.

A stirrup is adjustably secured to the lower ends of each pair of carrier rods 65, these stirrups providing means through which vertical vibratory motion is transmitted to the tray 26. Each stirrup comprises a cross-bar 78 attached at its ends to said rods, and a depending portion 79 extending to adjacent the base of the machine. A bearing seat 80 is formed in the lower end of the depending portion 79 directly below the center of the cross-bar 78 for the cylindrical bearing end 81 of the respective actuating yoke arm 82, one of said yoke arms being provided at each side of the machine to engage the respective bearing seats 80.

10 The yoke arms 82 are fixed to a transverse yoke shaft 86 which is mounted to rock in bearings 87 in the lower portion of the supporting structure 15 and extend forwardly and upwardly from said shaft.

15 Rocking of the shaft 86 in its bearings will impart vertical vibrations to the tray 26, causing the material therein to stratify, and the concentrate may be drawn off as desired through the central weir 33 and discharge spout 42. However, some of the finer parts of the material will sink through the perforations in the screen or grid and into the hutch 24 from which such constituents of the material may be drawn off 20 as hereinafter described.

25 The water is supplied to the machine by a pipe 90 which extends into the hutch and is provided at substantially the center thereof with a T-portion 91 having legs extending to positions adjacent opposite downwardly inclined walls thereof, and terminating in downwardly extending vents or nozzles 92. A valve 93 is provided in the pipe 90 to regulate the flow of water and thereby maintain the same at the desired level in the tray, and also furnish a continuous upward lift or classifying effect if this is desirable. With this construction and arrangement, the flow of water from the downwardly extending nozzles 92 will not agitate the 30 material on the tray. The pipe 90 preferably extends through the opposite sides of the supporting structure and through the housings 70, thereby serving as means for rigidifying these housings and preventing vibration thereof under 35 the reactions of the springs 73.

40 The power of the tray supporting springs 73 holds the bearing seats 80 firmly against the ends 81 of the yoke arms 82, so that the characteristics of the motion of said arms will be accurately transmitted to the tray. This is important, as both the characteristics and magnitude of the vibrations imparted to the tray must be accurately determined and set for the proper separation of the particular material to be treated. A vibration that would be effective in the separation of one ore or material is often ineffective or inefficient in the separation of another material, and a relatively small variation in either the characteristics or the magnitude of the vibrations, or both, will change an inefficient operation into a highly efficient and profitable one, particularly when operating upon an ore or material the gravities of the constituents of which differ only slightly.

45 According to the present invention, the tray

containing the pulverized ore or other material can be plunged suddenly downwardly in the water, and then raised more slowly. With the downward plunging stroke, the water flowing upwardly through the bottom perforations of the tray holds the pulverized ore in suspension, the heavier particles, which are usually the valuable mineral portion, sinking to the bottom first, whereas the lighter portions remain in suspension longer and settle more slowly. A slight pause can be given to the movement before raising the tray to permit the proper amount of settling, and the duration of this pause, in order to attain the most effective separation, is governed by the characteristics of the stroke.

When there is considerable difference of gravity between the mineral elements of ore and the other portions of a mixture, the separation may be readily and effectively accomplished, substantially without difficulty. However, when the difference in gravity of the constituents of the mixture is small a more appropriate type of stroke is necessary, in order to attain proper stratification, and this is particularly true in the separation by mechanical means wherein the strokes are more rapid and frequent than in hand separation by use of a sieve, such mechanical operation imparting a vibratory motion to the tray.

If the down strokes are too rapid or started too suddenly, jets of water are forced upwardly through the perforations in the tray which would cause undue agitation and remixing of the elements, and unless the upward or return strokes are properly timed or are too rapid, the necessary settling and stratification will not take place. It is therefore necessary that the characteristics of the vibratory movements of the tray shall be capable of fine adjustments to meet the requirements of the particular ore or other material to be treated.

The present invention provides mechanism for producing the most appropriate vibratory movements above mentioned, and for varying the characteristics and the length of the strokes. As shown in the present instance, such means is mounted in a housing 96 which is preferably closed so that the mechanism is protected from foreign substances and may run in an oil bath contained in the housing. The housing as shown comprises generally a bottom 37, side walls 98 and 99, end walls 100 and 101, and a top closure 102 secured in place as by screws 103, this housing being mounted in fixed position in the main frame on supports 95. A crank shaft 104 is mounted in said housing, it being journaled in bearings 105 and 106 in the walls 98 and 99 respectively. A cap 107 is fixed to the wall 99 at one end of the shaft 104, and it has a bearing adjusting cup 108 slidably mounted therein and bearing against the outer face of a tapered roller or other anti-friction bearing 105. An adjusting screw 109 is threaded through the cap 107 and bears against the cup 108. The bearing 106 at the other end of the shaft 104 is held in place by an open end cap 110 secured to the outer face of the housing wall 98. The shaft 104 extends beyond the cap 110 and carries a driving wheel preferably in the form of a fly-wheel 111 the rim of which is preferably grooved to receive belts 112 driven from a grooved pulley 113 on the shaft of a driving motor 114. The shaft 104 is provided with a crank 115 arranged within the housing 96, and a roller 117 is rotatably mounted on the eccentric pin 116, this roller including two

5 axially spaced cylindrical cam engaging portions 118. The rim of the driving wheel 111 is preferably relatively heavy to ensure steady and substantially uniform speed of rotation of the crank shaft.

10 The roller 117 is split diametrically into two similar halves to enable assembling of the roller on the crank pin, the halves of the roller being bolted together by bolts 121 which extend through lugs 119 located between the cam engaging portions 118, and the cam engaging portions of the roller are rigidly connected by bars 120. The inner faces of the lugs 119 and bars 120 constitute portions of the bearing of the roller on 15 the crank pin 116, and they are preferably spaced apart circumferentially to admit lubricant to the crank pin.

20 The roller 117 is split diametrically into two similar halves to enable assembling of the roller on the crank pin, the halves of the roller being bolted together by bolts 121 which extend through lugs 119 located between the cam engaging portions 118, and the cam engaging portions of the roller are rigidly connected by bars 120. The inner faces of the lugs 119 and bars 120 constitute portions of the bearing of the roller on 25 the crank pin 116, and they are preferably spaced apart circumferentially to admit lubricant to the crank pin.

20 A cam shaft 125 is mounted parallel to the shaft 104 to rock in bearings 126 and 127, the latter being located in a tubular extension 128 projecting from the side 99 of the housing 96. A cam lever 130 is mounted in the housing and keyed to the shaft 125, this cam lever having a cam block 131 mounted thereon for adjustment longitudinally thereof and having a pair of parallel cam faces which rest tangentially on the cylindrical portions 118 of the roller 117.

25 The cam faces on the cam block comprise straight portions 132 toward the outer end of 30 the cam lever and concave portions 133 which are tangential to the straight portions 132 and are curved in a direction toward the center of the shaft 104. The space 134 between the parallel cam engaging portions of the cam block 35 provides clearance for the bars 119 as the roller 117 is carried around by the crank pin 116.

30 The cam lever 130 is preferably provided with a hub 137 keyed to the shaft 125 and rigid with a pair of arms 138 which carry a pair of straight 40 outer portions 139 connected at their ends by transverse bars 140 and 141. Cam lever portions 139 constitute slide-ways 142 for the cam block 131, said block having longitudinal bearing faces 143 preferably parallel with the portions 132 of the cam faces and slidably engaging the same. 45 A clamping bolt 144 extends through the cam lever hub 137 for immovably securing the cam lever on the cam shaft, and a spacing collar 145 is provided on the shaft 125 between the cam 50 lever hub 137 and the adjacent wall 99 of the housing.

55 Means is provided for adjusting the cam block 131 longitudinally on the cam lever and for securing the cam block in different adjusted positions, such means comprising preferably an adjusting screw 147 extending between the portions 139 of the cam lever and threaded through a lug 148 on the upper face of the cam block. The screw 147 is mounted rotatably at one end in the cross bar 141, the head 149 of the screw abutting against the outer face of said bar, and a thrust collar 150 is pinned to the screw and engages the inner face of said bar. The head 149 and collar 150 thus maintain the screw pin in fixed axial position on the cam lever, and rotation of the screw will adjust the block longitudinally on the cam lever and thereby alter the position of the cam block relatively to the roller 117. After the cam block has been adjusted, it is locked in adjusted position by the screw 147 by setting up a lock nut 151 on the screw against the bar 140.

60 Adjustment of the cam block 131 toward the outer end of the cam lever 130 is limited by engagement of the lug 148 on the upper face of

65 70 75

the cam block 131 against the cross-bar 140 of the cam lever, and adjustment of the cam block toward the inner end of the cam lever is limited by engagement of the cam block with a shoulder 153 on the cam lever.

One end of the shaft 125 extends through and projects from extension 128 on the housing, and arm 158 is mounted on the projecting end of this shaft and has a hub 159 keyed thereto. A clamping bolt 160 secures the rocker arm against lateral movement on this shaft.

The rocker arm 158 extends toward the oscillatory yoke shaft 86, and is preferably provided with a laterally offset flange 161, the upper face of which is provided with a hardened steel wear plate 162.

A torque lever 165 is mounted on and fixed to the yoke shaft 86, this torque lever 165 carrying a hardened roller 166 which is held in continuous engagement with the rocker-arm plate 162 under the influence of the tray supporting springs 73, as will be clear from Fig. 23.

Any movement imparted to the cam lever 130 by the roller 117 on the crank pin 116 will be transmitted to the tray through the medium of the rocker arm 158, torque lever 165, and yoke arms 82, but in the relatively opposite direction; that is, any upward movement of the cam lever 130 will cause the yoke levers 82 to move downwardly, and vice versa. The direction of movement of the several parts mentioned when the cam lever is lifted, is indicated in Fig. 23 by the arrows applied to each of the several parts. When the cam lever moves downwardly the direction of movement of said parts is reversed. Therefore, any changes in the characteristics of the stroke due to the adjustment of the cam block relatively to the roller 117, will be transmitted to the separating tray 26.

The tray supporting springs 73 not only hold the roller 166 in engagement with the rocker arm 158, but they also, by forcing said arm downwardly, tend to hold the cam block 131 continuously in engagement with the roller 117. However, when the stroke called for is extremely short, which is the time it is most necessary for the machine to be most sensitive to the characteristics of the strokes as developed by the action of the roller 117 upon the cam 131, the pressure from the main springs 73 is least effective to maintain this contact. It is therefore preferable, in order to insure transmission to maintain the desired characteristics of the repeated vibratory strokes during operation at such times, to provide auxiliary means for ensuring maintenance of continuous contact of the cam block with the roller 117. Such auxiliary means comprises preferably a helical torsion spring 168 enclosed in a spring housing 169 secured upon the housing 96 in axial alignment with the cam shaft 125. A cap 170 closes the outer end of the spring housing 169, as shown in Fig. 10, and is provided on its inner face with a boss 171 having a slot 172, and a similar slot 173 is provided in the adjacent end of the cam shaft 125. The ends of the spring 168 are bent diametrically inwardly as at 174 and 175 to engage within the slots 172 and 173 respectively.

The cap 170 is rotatable upon the outer end of the spring housing 169 to adjust the power or loading of the spring 168, and accordingly, the pressure of the cam block upon the roller 117. The cap 170 is held in different positions into which it may be rotated by bolts 176 extending through the cap 170 and through a flange 177

on the outer end of the spring housing 169, three bolts spaced equidistantly being shown for this purpose. The periphery of the cap 170 is provided with a series of wrench-receiving notches, for adjusting.

From the foregoing it will be apparent that the characteristics of the stroke imparted to the tray is determined by the character or shape of the cam faces 132-133 of the cam block 131 and the position of the cam faces relatively to the roller 117 on the crank shaft 104.

Figs. 18 and 19 show diagrammatically the movements of the cam block 131 and hence of the cam lever 130 when the cam block is adjusted on the lever so that only the straight portions 132 of the cam faces are within the range of the throw of the eccentrically mounted roller 117, and Figs. 20 and 21 show diagrammatically the movements of the cam lever when the cam block is adjusted to the outermost position with the curved portions 133 of the cam faces entirely within the range of operation of the roller thereon. In Fig. 22 the strokes produced as the result of said adjustments, as transmitted to the tray are plotted, it being understood that the strokes as transmitted are in the reverse direction from those of the cam lever, as hereinbefore stated, and as indicated by the arrows in Fig. 23.

In Figs. 18 to 21 inclusive, 185 indicates the center of rotation of the cam shaft 125, and the circle 186 indicates the throw of the eccentric of the crank shaft, that is, the path of movement of the center of the roller 117. This circle is divided into twenty-four equally positioned successive stations of the eccentric during one revolution of the crank shaft, said positions being designated by the numerals 1 to 24 inclusive.

With each of these stations as a center, and assuming the rotation to be in the direction of the arrows, the successive positions of the cam block engaging periphery of the roller are designated by the circles designated 188. To avoid confusion, the twelve successive positions of the downstroke of the eccentric roller are illustrated in Fig. 18, and the successive positions thereof during the up-stroke are indicated in Fig. 19.

Lines 132a tangential to each of said circles 188 indicate both the vertical and the angular position of the cam face 132 at each of said stations of the eccentric roller. From the center of rotation 185 of the cam lever, through a given point 132b at the end of the cam, are drawn radial lines 187 to intersect an arc 188 the center of which is the center of rotation of the cam shaft 185. From the points of intersection of the lines 187 and the arc 188, lines 189 are drawn parallel to the plane 190 intersecting the axes of the shafts 116 and 125, to a line 191 perpendicular to said plane. The points of intersection with the line 191 are indicated by the characters 1' to 24' inclusive, and these points are plotted in Fig. 22, but in reverse, so that the movement as depicted by the dotted line 192 will indicate the movement transmitted to the tray 26. Due to the reduced size of the diagrams, the radial lines to the points 132b are produced to the arc 188 in order that the plotted curves indicating the movements may be more distinct and legible.

In Figs. 20 and 21 the same method is employed for illustrating the motion when the cam block is adjusted outwardly on the cam lever to bring the curved portions 133 of the cam block into full engagement with the roller faces 118. By plotting the motion in the same manner, the curve is depicted in Fig. 22 by the full line 193. This lat-

ter motion provides for a shorter pause at the upper end of each stroke than in the case illustrated by Figs. 18 and 19, and for a quicker or more sudden initial downward movement which tapers off at the bottom of the stroke, giving a longer period of rest for settling and stratification to take place before beginning the upward stroke. It will be apparent that various minute adjustments of the cam block between those represented by these diagrams may be made to vary the characteristics of the stroke to suit the nature of the ore or other material to be treated.

Since the eccentric roller during its upward swing operates on the portion of the cam face near the pivotal center of the cam lever, the latter will be swung upwardly and consequently the tray will be plunged downwardly rapidly, and during the downward swing of the eccentric roller it operates on the outer portion of the cam face at a relatively greater distance from the pivoted center of the cam lever, the latter will swing downwardly and consequently the tray will be raised more slowly, the movements imparted to the tray will be differential. The rapid descent of the tray and relatively slow rising thereof afford the material suspended in the water in the tray ample time to stratify in accordance with the different specific gravities or settling rates of the constituents, and such stratification is aided by the prolonged period of rest of the tray while at the termination of its downward stroke. The adjustments of the cam to cause the eccentric roller to cooperate with the straight portion or the curved portion, or partly on one and partly on the other of said portions, enable the characteristics of the strokes to be varied widely according to the nature of the materials being treated, or the fineness or coarseness thereof.

In addition to the means for varying the characteristics of the strokes imparted to the tray, means are also provided for adjusting the length of the strokes without varying the characteristics thereof, which is advantageous in the separation of some ores or other materials or the size of the particles thereof. To this end, means are provided for adjusting the roller 166 longitudinally on the torque lever relatively to the rocker arm 158, it being evident that the closer this roller is to the shaft 125 and further from the shaft 86, the shorter will be the strokes, and that the further this roller is from the shaft 125 and closer to the shaft 86, the longer the strokes.

The torque lever 165 preferably comprises a casting providing two similar parallel spaced members 197, each providing an elongated outer rail portion 198, a hub portion 199, and a yoke shaped portion 200 which connects the rail and hub portions. Transverse members 201 and 202 extend between the members 197 and connect them at their outer and inner ends respectively. The hub portion 199 is provided with a key 203 for fixing it to the shaft 86, and the hub portion 199 is preferably split and provided with a bolt 204 for clamping it firmly to said shaft.

The roller 166 is journaled in a block 205 which is preferably coextensive in width with the torque lever 165, and is provided with bearing faces 206 engaging the under faces of the rail portions 197 which constitute slide-ways for the block.

An adjusting screw 208 is mounted rotatably in the cross-members 201 and 202, this screw having a threaded portion 209 engaging and extending through a similarly threaded lug 210 projecting upwardly from the block 205. A

crank 211 is pinned to the outer end of the adjusting screw and bears against the outer face of the cross member 201, and the opposite end of the screw is provided with a hand wheel 212 for rotating it. A spring 213 is interposed between the member 202 and hand wheel to hold the screw frictionally in any position into which it is rotated. A lug 214 at the forward end of the block 205 projects upwardly between the rails 198 of the torque lever to prevent lateral movement or twisting of the block, relatively to the lever.

According to the construction described, the roller 166 may be readily adjusted longitudinally 15 of the torque lever 165, by rotating the screw 208, to vary the length of the strokes imparted to the tray 26. By locating the hand wheel 212 adjacent the shaft 86, this adjustment may be made with facility while the separator is in operation, the yoke-shaped portion 200 giving ample space for the hand in operating the hand wheel 212.

A suitably graduated scale 215 is preferably provided on a side of the torque lever to cooperate 25 with the block 205 and thereby indicate the different adjustments of the roller 166 relatively to the torque lever.

As hereinbefore stated, some of the heavier 30 finer portions of the ore or material pass downwardly through the screen 48 and sink into the hutch 24 from which they are recovered. The hutch comprises generally an upper portion 225, a main body portion 226, and a discharge spout 227.

35 The upper portion 225 of the hutch which lies immediately below the flexible diaphragm 57 is substantially coextensive in area therewith, and slopes downwardly at an angle sufficient to avoid interference with the vertical vibratory movements of the tray support 51. The main body 40 portion of the hutch of inverted pyramidal shape has relatively steeply sloping sides, and it terminates in a spout portion 227, which is preferably rectangular in cross-section. This formation of the hutch provides ample space within the limits 45 of the main frame to accommodate all of the actuating mechanism, including the housing 96, motor 114 and sheave 111.

Means is provided for drawing off material 50 collected in the spout portion 227 of the hutch, such means comprising in the present instance a nozzle member and cooperating means for controlling the discharge therefrom. The nozzle member comprises a rectangular plate 228 having a groove 229 in the upper face thereof to receive the lower edge of the spout 227, and a centrally disposed funnel shaped discharge orifice 230. The plate 228 is held in place by bolts 231 extending through lugs 232 on the plate 55 and brackets 233 fixed to the spout 227.

An arm 234 extends laterally from one edge of the plate 228 and terminates in a sleeve 235 in which a downwardly extending pin 236 is mounted. Concentric with the pin 236 is an arcuate 60 boss or rib 237 through the center of which extends the lower end of the orifice 230. A discharge plug holder is mounted on the pin 236, this holder comprising a lever 238 having two downwardly tapering pockets 239 and 240 respectively to receive rubber plugs 241 and 242 which may be selectively brought into position under the discharge orifice 230. The pockets 239 and 240 are open at the bottom except for peripheral flanges 243 on which the plugs rest. Either of 65 70 these plugs may be solid or imperforate, or pro-

vided with a discharge orifice 244. The lever 238 is provided with lugs 245 one or the other of which is engageable with a lug 246 on the plate 228, when the respective plugs are in position under the hutch discharge orifice 230. When a solid plug is under the hutch discharge orifice the hutch is closed and the particles sinking from the tray will accumulate in the portion 227. When it is desired to draw off particles accumulated therein, the lever is swung into a position to bring the plug 241 under the opening 230 as illustrated in Figs. 5 and 6. A plurality of plugs 241 having different size discharge openings 244, may be provided for use interchangeably according to the character of the accumulation to be discharged from the hutch, or if the discharge is substantially heavy an open plug of suitable size may be left in position for continuous discharge.

The lever 238 is preferably provided with an elongated bearing sleeve 247 mounted on the pin 236, and a compression spring 248 is interposed between the lower end of said sleeve and a collar fixed to the lower portion of the pin, for yieldingly holding the plugs on the lever in water-sealing engagement with the outlet end of the nozzle.

The lever 238 is provided with a handle 250 for operating it, and in order to enable this handle to be reached through the opening 22 and operated, the discharge spout 227 of the hutch is preferably inclined laterally toward this opening, thereby placing the handle within convenient reach through this opening.

The opening 21 in the enclosing casing also provides convenient access to the top 102 of the housing 96 to enable this cover to be removed and the interior of this housing reached for adjustment of the screw 147 to vary the characteristics of the strokes or for lubrication or other servicing of the mechanism contained in this housing, and the openings 21 and 22 also provide easy access to the crank 211 or hand wheel 212 for adjustment of the screw 208 to vary the length of the strokes, and enables other parts of the mechanism within the casing to be reached for servicing or other purposes.

In the operation of the jig to separate materials having different settling rates, the segregation of the materials within the tray should pass through alternate phases of semi-fluidity and compactness, and the weir arrangement for discharging distinct strata as separate products takes advantage of the semi-fluid condition of the material on the downward pulsation of the tray to effect the separation. After the strata of material have been formed in the tray, the desired depth of the entire bed of material is established by adjusting the height of the weirs 34 to the same level, the weir 33 is brought up substantially to the level of the weirs 34, and the concentrate cup 40 is then lowered into the stratum of heavy material. The minimum distance between the lower edge of the cup 40 and the material supporting screen 48 will be dictated by the size of the largest particle of heavy material which should pass between the cup and screen. The weir 33 is then lowered so that discharge of particles from within the cup is induced only on the downward plunge of the tray. Such discharge is due to the longitudinal flow of the material induced by the difference in depth of the bed at the feed and discharge ends of the tray, the material having a tendency to level out while it is in a semi-fluid state during and immediately following the downward plunge of the tray. The lighter or slower settling particles are prevented from entering the

cup area due to the heavy stratum into which the cup projects. However, since the entire bed made up of all strata has a certain head, the heavy stratum will be forced up into the cup until this head is balanced by the material within the cup. After such balanced condition has been established, the discharge is substantially self-compensating over considerable variations in the quality and quantity of the feed. It is to be understood that by providing each jig with multiple cups and weir arrangements set at different elevations, it is possible to take off a greater number of components of the material.

I claim:

15. 1. In a separator having a foraminous support to receive material to be separated and mounted for substantially vertical movements, and means for submerging said support in liquid, means including a cam connected to said support and having a straight portion and a curved portion tangential thereto and an operating member continuously engaging the cam and cooperative alternately with said straight and curved portions of the cam for imparting sudden downward movements to said support to suspend the material thereon, and relatively slower upward movements to effect stratification of the material.
20. 2. In a separator of the type having a foraminous support to receive material to be separated and movable substantially vertically while submerged in a liquid, means including a cam member connected to said support and having a curved portion and a straight portion tangential thereto and an operating member engageable continuously with the cam member and cooperative alternately with said curved and straight portions of the cam member for imparting sudden downward strokes to said support to suspend the material thereon and relatively slower upward strokes thereto, and means for varying the operative relationship between said members to provide variable periods of rest at the extremities of the downward strokes.
25. 3. In a separator of the type having a tray having a perforated support to receive material to be separated and movable upwardly and downwardly while immersed in water, and means for discharging separated constituents of the material from the tray, means including a cam member connected to the tray and having a curved portion and a straight portion tangential thereto and an operating member continuously engaging the cam member and cooperative alternately with the curved and straight portions of the cam member for imparting differential upward and downward movements to the tray, and means for modifying the operative relationship between said members to vary the characteristics of said downward movements independently of said upward movements.
30. 4. Jigging mechanism for a separator of the type having a substantially vertically movable separating tray, comprising means including a cam member connected to the tray and having a curved portion and a straight portion tangential thereto, and a cooperating operating member engageable alternately with said curved and straight portions of the cam member for imparting differential movements to the tray, means additional to said means and adjustable to vary the length of the movements imparted to the tray, and means for varying the operative relationship between said members for varying the characteristics of said differential movements while maintaining the length of said movements.

5. In a separator of the class described, a hutch adapted to contain a body of water, a foraminous tray having means for feeding thereto material to be separated, means for resiliently supporting the tray in the water in the hutch and constantly tending to move the tray upwardly, a flexible diaphragm connecting the tray to the hutch means including members connected to the tray for imparting movements to the tray to force it downwardly against the action of said supporting means and for controlling the upward return movements of the tray under the action of said supporting means, means interposed between the tray and said members for adjusting the height of the tray relatively to said members to level the diaphragm, and means interposed between the tray and the resilient supporting means and operative upon said supporting means to adjust the power of said supporting means while maintaining the adjustment of the height of the tray.

6. In a separator of the class described, a foraminous tray to receive material to be separated, means for resiliently supporting the tray in water and constantly tending to move the tray upwardly, means including an operating member and a cam member connected to the tray and having a curved portion and a straight portion adjacent thereto and cooperable alternately with the operating member and held by said supporting means in continuous cooperative relation with said operating member for imparting movements to the tray to force it downwardly against the action of said supporting means and for controlling the upward return movements of the tray under the influence of said supporting means, and means for varying the operative relation between the operating member and the curved and straight portions of the cam member to change the characteristics of the downward movements independently of the upward movements imparted thereby to the tray.

7. In a separator of the class described, a casing having means therein to contain a body of water, a foraminous tray to receive material to be separated, means exteriorly of the casing for resiliently supporting the tray in water in the casing and constantly tending to move the tray upwardly, members connected to and extending downwardly from the opposite sides of the tray and exteriorly of opposite sides of the casing, bearings at the lower portions of said members, an oscillatory lever positioned exteriorly of the opposite sides of the casing adjacent each of said members and operably engaging said bearings, and means including a yoke shaft rigidly fixed to said levers and extending through the lower portions of the opposite sides of the casing for imparting downward movements to said members and the tray and for controlling the return movements of the tray under the influence of said resilient means.

8. In a separator of the class described, a hutch adapted to contain a body of water, a stationary frame, a foraminous separation tray, a tray-supporting frame, a flexible diaphragm connecting the periphery of the tray-supporting frame to the hutch, lateral extensions fixed to the respective sides of the tray supporting frame and disposed above the said frame, a pair of longitudinally spaced compression springs arranged between each of said lateral extensions and said frame, members rigidly connected to and extending downwardly from said lateral extensions exteriorly of opposite sides of the frame, means

for adjusting the height of said lateral extensions of the tray-supporting frame to level the diaphragm, and means engaging said members for imparting downward movements to the tray and for controlling the return movements thereof under the action of said springs.

9. A separator as defined in claim 8, including means carried by said lateral extensions and cooperative with the respective pairs of springs for adjusting the power of said tray-supporting springs.

10. In a separator of the class having a foraminous tray to receive the material to be separated and mounted for substantially vertical movements in water, means for jiggling the tray comprising a driving shaft, a cam shaft having means for rocking it by the driving shaft, a rocker arm fixed to the cam shaft, a yoke shaft parallel with the cam shaft, a torque lever fixed to said yoke shaft, a roller carried by the torque lever and engaging the rocker arm, yoke arms fixed to the yoke shaft, means operatively connecting said yoke arms to the tray, and means for varying the operative relationship between the roller and the rocker arm and torque lever to vary the amplitude of the movements imparted to the tray.

11. In a separator as defined in claim 10, wherein said roller is adjustable longitudinally of said torque lever and rocker arm to vary the length of the strokes imparted to the tray from said cam shaft.

12. In a separator of the class having a perforated tray to receive material to be separated and mounted for substantially vertical movements in water, means for jiggling the tray comprising a driving shaft having a roller mounted eccentrically thereon, a cam shaft, a cam lever rigidly fixed to the cam shaft, a cam on said lever having a cam face in continuous engagement with said roller, said cam face having a curved portion and a straight portion tangential thereto, and means operatively connecting the cam shaft to the tray for imparting reciprocatory strokes to the tray.

13. In a separator as defined in claim 12, wherein said cam is adjustable longitudinally of said cam lever to bring different areas of said portions of its cam face into cooperative relation with said roller.

14. A separator of the class having a perforated tray mounted for substantially vertical movements, means for jiggling the tray comprising a driving shaft having a roller mounted eccentrically thereon, a cam shaft having a cam lever fixed thereto, means operatively connecting the cam shaft to the tray for controlling upward and downward strokes thereof, and a cam block mounted on said lever and having a cam face thereon comprising a curved portion and a straight portion tangential thereto and alternately cooperative with said roller, the cam block being adjustable in a direction toward or from the cam shaft and longitudinally of the cam lever to bring more or less of the curved portion of the cam face into cooperative relation with said roller and thereby vary the characteristics of the downward strokes of the tray independently of the amplitude of its strokes.

15. Jiggling mechanism for a separator of the class having a perforated tray to receive material to be separated, comprising a driving shaft having a roller mounted eccentrically thereon, a cam shaft, a cam lever rigidly fixed to the cam shaft, a cam on said lever engaging said roller, a rocker arm fixed to the cam shaft, a yoke

shaft and toward which the rocker arm extends parallel with the cam shaft, a torque arm fixed on the yoke shaft and extending toward the cam shaft, a roller carried by one of said arms and engaging the other arm, yoke arms fixed to the yoke shaft and operatively connected to the tray, means for adjusting the cam longitudinally on the cam lever, and means for adjusting said roller longitudinally relatively to both the rocker arm and torque arm.

16. Jigging mechanism for a separator of the class having a perforated tray mounted for substantially vertical movements in water, comprising a driving shaft having a roller mounted eccentrically thereon, a cam shaft, a cam lever fixed to the cam shaft, a cam block carried by said lever and having a cam face engaging said roller, said cam face having a straight portion and a curved portion tangential thereto, means for adjusting the cam block longitudinally on the cam lever toward or from the cam shaft to bring the different areas of said portions of the cam face within the range of engagement of said roller therewith, and means interposed between the cam shaft and the tray for transmitting the characteristic motion of the cam shaft to the tray.

17. Jigging mechanism for a separator having a tray supported in water for substantially vertical movements, comprising means for producing differential vibratory movements, a vibratory rocker arm connected to said means to receive

vibratory movements therefrom, a shaft toward which the rocker arm extends and having a torque lever fixed thereto and extending therefrom toward the axis of vibration of the rocker arm, a roller carried by the torque lever and engaging said rocker arm, means for connecting said shaft to the tray, and means for adjusting said roller longitudinally relatively to the torque lever and the rocker arm to vary the length of strokes transmitted to the tray.

ULYSSES S. JAMES, JR.
